C. N. WEEMS

REFLECTOR FOR HEADLIGHTS

Filed Nov. 15, 1924

Patented July 27, 1926.

1,593,784

UNITED STATES PATENT OFFICE.

CHESTER N. WEEMS, OF ATLANTA, GEORGIA, ASSIGNEE TO ATLANTA KILCO CORPORATION, OF ATLANTA, GEORGIA.

REFLECTOR FOR HEADLIGHTS.

Application filed November 15, 1924. Serial No. 750,082.

This invention relates to an improved headlight and is of the type that is described and claimed in my previous United States Patents #1,398,987, issued December 6, 1921, and #1,349,642, issued August 17, 1920. These prior patents describe a reflector with a central partition and which comprises two reflectors of different placement relative to the source of light so that the upper and lower halves both reflected the rays so that they inclined downwardly from the lamp. This provides a non-glare reflector, that is, the field above the horizontal axis of the lamp was not pierced by direct or sharply reflected rays. In the previous patents, it was necessary to incline the light bulb and, furthermore, the light bulb holder was mounted directly on the horizontal partition or plate. To make the reflector with the lamp bulb holder and the partition attached independently to the reflector and to provide a horizontal bulb support and still conform to the reflective functions of my headlamp, is the purpose of this invention.

The present invention therefore provides a reflector that is insertable in the existing headlamp shells or casings. In other words, it is a reflector of two reflecting surfaces which may be readily manufactured as a single unit, suitable for replacing the old forms of reflectors in the standard shells.

Another object of the invention is to provide a device for adjusting the bulb support so that it is accessible from the front and by means of which the bulb can be advanced or retracted and in this way the light centre can be properly located while the lamp is burning so that much time can be saved and a proper adjustment quickly arrived at.

The invention is illustrated in the accompanying drawing in which Figure 1 is a section of a reflector made according to my invention, the bulb and the bulb support being shown in elevation. Figure 2 is a section on line 2-2 in Figure 1 and Figure 3 is a top view partly broken away of the horizontal partition that can be used in the device.

The upper and lower halves of the reflectors are dissimilar, that is, on each side of the centre the reflecting surfaces are arranged at different angles and with a different curvature which will not be described technically in this specification having been fully described in my prior patents and, furthermore, for the reason that the invention

is adapted for use with the various types of dissimilar reflecting surfaces on the top and bottom halves.

The upper half shown at 10 reflects the rays from the light source 11 so that the reflected rays cross the horizontal axis of the lamp and project downwardly on the roadway. The lower half 12 is designed so that the rays reflected by it from the light source 11 do not cross the axis but are projected below the horizontal centre of the reflector to fully illuminate the roadway but not extending upwardly to a sufficient height to cause glare in the eyes of approaching motorists or pedestrians.

These dissimilar reflecting surfaces approach the horizontal axis at different angles and to provide for merging these dissimilar surfaces and to form a support to provide for a horizontal supporting of the light bulb, I provide a flattened central portion 13. The lamp support 14 is placed in this flattened portion, the lamp support usually being a cylindrical tube which is crimped as at 15 to embrace the edges of an opening made in the flattened portion. The lamp support is thus held with its axis parallel with and usually in line with the central axis of the headlamp.

The two dissimilar reflecting surfaces 10 and 12 can thus be made of one piece or if desired, of two halves secured together and the front edge 16 is circular so that it can be fitted in any of the usual existing and standard headlight shells. The light is supported in a suitable socket 17 which is slideable in the lamp support and receives the bulb 18. This disposition of the socket permits of its use in the existing lamp shells or casings and it can be adjusted from the front, the flattened portion being utilized by supporting a screw 19 in the flattened portion, the screw being held against longitudinal movement by such means as a collar 20 in the rear of the flattened portion and a screw head 21 in the front thereof so that a screw driver can be used from the front of the reflector to turn the screw 19 which adjusts the reflector because there is a connection between the socket 17 and the screw 19 which in the form shown comprises a nut 22 which it will be readily observed, will be advanced or retracted according to which way the screw 19 is turned.

This is of particular advantage inasmuch as

- as when official tests of adjustments of head-lights are required, the owner may be reasonably assured that the focus of the head-light has not been tampered with after the 5 official test has been made which is not the case in those types where an adjustment is made from the outside of the shell making it easy for inexperienced persons to tamper with the focus of the headlight.
- 10 To focus this headlight the adjustments can be made without removing the reflector unit from the shell and while the light is burning. It is only necessary to open or remove the door of the shell and the results 15 of the adjustment can be viewed so that the defects can be seen at once in contrast with the successive lighting and extinguishing of the lamp while adjustments are being made in the old way.
- 20 In this form of headlight it is usual to provide a horizontal partition 23 which is placed to coincide approximately with the plane of the junction line at which the two dissimilar reflecting surfaces are joined. The 25 partition may be held in place in any suitable way usually by lugs 24 which can be inserted through slits in the reflector and then slightly turned to lock the partition in place. The partition has a small hood or 30 sub-reflector 25 at the front end of an opening 26 which receives the bulb 18, this small reflector 25 preventing rays of light passing directly from the light source to the forward 35 upper half of the area or field which is the glare zone.
- At the rear of the opening 26 I strike up a shield 27 which is disposed so that it prevents rays from the light source striking the flattened portion 13. This prevents the flattened portion of the upper reflecting surface from reflecting light in directions apt to cause glare. While this shade or shield is 40 in the preferred arrangement attached to the horizontal plate or partition, it may be
- mounted or attached in any convenient way 45 to serve this purpose. The partition also serves the useful purpose of shielding either of the two dissimilar reflecting surfaces from much of the diffused light emitted by the opposite reflecting surface. The reflection of diffused light emitted by the reflecting surfaces themselves is the source of some uncontrolled illumination in directions tending to cause glare in headlamps and the use of a horizontal partition through the space 50 encompassed by the reflector unit, reduces the amount of such uncontrolled flux.
- It is therefore possible by this invention to use a reflector with two dissimilar reflecting surfaces, the front edges of which are 55 insertible in a circular shell or casing and the rear parts of the reflector or central part of the bowl where these reflecting surfaces overlap is so made that both the upper reflecting surface and the lower reflecting surface 60 are flat in the same vertical plane so that the two halves coincide at the point of juncture.
- I claim:
- A reflector for headlights which is formed 70 of sheet metal with its upper and lower halves designed with a different curvature relative to the central axis so that the halves reflect rays in the same general direction, the central portion of the reflector where 75 these halves meet being flattened, a socket for a bulb at the lower part of the flattened portion, an adjusting means for the socket, said means being accessible at the upper part of the flattened portion and from the 80 front, and a shield between the bulb and the flattened portion to prevent rays from the bulb being reflected by said portion.
- In testimony that I claim the foregoing, I have hereto set my hand, this 29 day of 85 October, 1924.

CHESTER N. WEEMS.
